SHOESHINE BOX

Samuel Friedman, Brooklyn, N.Y., assignor to Re-Ly-On Metal Products, Inc., Brooklyn, N.Y., a corporation of New York

Filed Mar. 3, 1961, Ser. No. 64,131

Term of patent 14 years

(Cl. D9—2)

FIG. 1

FIG. 2

FIG. 4

FIG. 3

FIG. 5

FIG. 1 is a perspective view of the top, one side and end of a shoeshine box, showing my new design;

FIG. 2 is a rear elevational view in carrying position;

FIG. 3 is a side elevational view of the shoeshine box in carrying position, showing the side opposite that shown in FIG. 1;

FIG. 4 is a top plan view of the shoeshine box in the position shown in FIGS. 2 and 3; and

FIG. 5 is a bottom plan view thereof.

The shoe plate and side trim strips are lined to represent scoring.

I claim:

The ornamental design for a shoeshine box, as shown and described.
